UNITED STATES PATENT OFFICE.

JOSEPH C. FIELD, OF ORANGE, NEW JERSEY, ASSIGNOR, BY MESNE ASSIGNMENTS, TO
WESTERN ELECTRIC COMPANY, INCORPORATED, A CORPORATION OF NEW YORK.

HIGH-CAPACITY SELECTIVE SIGNALING SYSTEM.

1,371,748.

Specification of Letters Patent. Patented Mar. 15, 1921.

Application filed June 24, 1911. Serial No. 635,093.

To all whom it may concern:

Be it known that I, JOSEPH C. FIELD, citizen of the United States, residing at Orange, in the county of Essex and State of New Jersey, have invented a certain new and useful Improvement in High-Capacity Selective Signaling Systems, of which the following is a full, clear, concise and exact description.

This invention relates to party lines selective signaling systems and more particularly to a telephone train despatching system employing a plurality of step-by-step selective devices adapted to be advanced in unison under control of apparatus at a sending or despatching station, each selector being adapted to close a signaling contact at some point in its movement, the position of such closure being different for each selector so that the signaling contacts at no two stations on the same line will be closed simultaneously.

In the particular class of selective systems to which this invention relates, it has been the practice heretofore to arrange all of the selectors on the line so that each will operate in response to a different number of current impulses from a sending station to close its signaling contact, thus requiring as many operating impulses as there are selectors on the line in order to bring about the closure of all of the signaling contacts of all of the selectors on the line. While such an arrangement works satisfactorily where the number of selectors on the line is not large, the efficiency and speed with which signaling takes place naturally decreases as the number of selectors on one line increases and it is the object of this invention to so arrange a system of these selectors that many more may be operated over the same line with a given number of impulses than it has been possible to operate heretofore with the same number of impulses.

One of the features of this invention relates to the particular means here employed for attaining the above object and consists in an organization of the circuits and apparatus such that the operation of selecting a particular station on the line is accomplished by first stepping all of the selectors around in unison, releasing a group of the operated selectors including the one at the selected

station and again stepping the selectors forward until the signaling contact of the selector in the released group which corresponds with the desired station is closed.

Another feature of this invention relates to a novel means of bringing about the release of the selectors in a certain group and consists essentially in so equipping the selectors that at a certain position in their movement a circuit will be closed which will short-circuit holding magnets of the selectors in that group and thus cause their release. The various groups are arranged to be released on different numbers of impulses.

A third feature of this invention relates to a novel means for preventing the bells at the various way stations tapping on passing contacts and consists in so associating the bell circuit and the operative parts of the selector that said bell circuit will only be closed upon the release of a slow-acting holding magnet which occurs upon the closure of certain contacts controlled by the selector.

The details of apparatus and circuits are also features of this invention.

In the drawings—

Figure 1 is a circuit diagram of a selective signaling system embodying my invention;

Fig. 2 is a detail view of the selector parts and circuits in the releasing position of the selector;

Fig. 3 is a detail view of the selector parts and circuits with the signaling contact closed, and

Fig. 4 is a fragmentary detail view of the selector showing the arrangement of the contact springs.

In Fig. 1 of the drawing a selective signaling system embodying this invention is shown equipped with two groups of selectors A and B, each group including selectors C, D and E with the selectors C of each group shown in detail. The selector C of group A is shown as arranged for local battery signaling, that of group B being arranged for common battery signaling, either arrangement being capable of use in a system embodying this invention. In actual practice the local signal circuits of a system will probably be arranged to operate either all local battery or all common battery.

Located at the sending or despatching end of line wires 10 and 11 is an impulse transmitter 12 comprising a rotating disk 13 provided with teeth 14 on its periphery adapted 5 as said disk 13 rotates to close a contact 15 for completing a circuit from a local battery 16 through the winding of an impulse relay 17. The operation of the impulse relay 17 intermittently connects and disconnects battery 18 with the line wires 10 and 11 to operate the selectors. Retardation coils 19, 20 and 21 connected in the line wires and a condenser 22 bridged across said line wires cooperate to smooth out the current impulses 10 sent over the line for selecting purposes so that there will be no disagreeable thump in any telephone receiver which may be bridged across the line during selection. A non-inductive resistance 23 normally in 15 bridge of the line wires 10 and 11 through a contact on the impulse relay 17 is intermittently disconnected from and connected therewith by the operation of said impulse relay. This non-inductive resistance 23 forms a low resistance discharge path for 20 the retardation coils 19, 20 and 21 and the condenser 22 so that the current impulses over the line will not be prolonged to an extent that will cause the sticking of the selector magnets in case the line is of too high 25 resistance. 25 designates a despatcher's telephone set which is normally across the line wires 10 and 11 at the despatcher's station. The impulse transmitter 12 may be made adjustable by means of segments 26 and 27 30 adjustably secured to one face of the disk 13 and adapted to vary the number of teeth effective for calling purposes.

The selectors used in this system are alike 35 in principle and operation and a description of one will suffice for all. As shown each selector embraces a slow-acting magnet 30 hereinafter termed a holding magnet, a quick-acting magnet 31 hereinafter termed 40 the stepping magnet, and a ratchet wheel 32 adapted to be rotated in one direction under control of the holding and stepping magnets 30 and 31 and returned to normal by means of a coiled actuating spring 33. The holding and stepping magnets are connected in 45 series in bridge of the line wires and control armatures 34 and 35 respectively. Carried by the armature 34 are two angularly disposed arms 36 and 37, the arm 36 being in 50 engagement with a holding pawl 38 and the arm 37 being in engagement with a stepping pawl 39 carried by the armature 35. The movement of the armature 34 due to energization of the magnet 30 permits the pawls 55 38 and 39 to be moved into position to engage the ratchet wheel 32 by the action of the spring 40 and 41 respectively.

Referring now to the details of the selector by means of which the various features of this invention hereinbefore enumerated

ated are attained it will be noted that the ratchet wheel 32 carries two contact arms 50 and 51 adapted in the rotation of said ratchet wheel to be brought separately into engagement with a contact spring 52 located adjacent said ratchet wheel. The spring 52 is in mechanical engagement with the stepping armature 35 through a projecting arm 53 (see Fig. 4) on said spring which engages an insulating button carried by said arm. 75 The tension of said spring being in a direction to force it toward said armature 35, said spring will partake of the motion of said armature during the stepping movement thereof. A second contact spring 54 mounted adjacent to the spring 52 and in line therewith normally bears against an insulating pin 55 on the stepping armature 35 when the selector parts are in their normal or inoperative position and against an insulating button 56 on the outer end of the arm 37 when the holding magnet is energized and its armature 34 is in its attracted position. As shown in the drawings the arm 51 carried by the ratchet wheel 32 is slightly longer 80 than the arm 50 and is located slightly in advance of said arm 50. These arms are adapted to coöperate with the contact springs 52 and 54 in the following manner:

When the shorter contact arm 50 is 95 brought into position to engage the contact spring 52 as shown in Fig. 2, it pushes the said contact spring away from engagement with the armature 35 and the contact made by the engagement of said arm 50 with said contact spring 52 completes a short circuit of the holding magnet 30. This causes the deenergizing of the holding magnet 30 and permits the armature 34 thereof to drop back to normal position. The contact spring 54 100 remains in contact with the arm 37 until it comes into engagement with the insulating pin 55. The relation of the arm 50 with respect to said pin 55 is such however that the spring 54 is stopped before it makes contact with the spring 52 and as the spring 54 is in the bell circuit there will be no signal sounded when the arm 50 and the spring 52 are in engagement. If, however, the arm 51 105 is the one brought into contact with the spring 52 as shown in Fig. 3 the relation of the parts will be changed. In this position of the parts the engagement of the arm 51 with the spring 52 will complete the short circuit of the holding magnet 30 as in the former case but the arm 51 being longer than the arm 50 the contact spring will be held in a position beyond the outer end of the insulating pin 55 so that as the spring 54 follows the arm 37 forward upon the release of the holding magnet armature 34 said spring 54 110 will be brought into contact with the spring 52 and a circuit will be completed for a signal 115 60.

In the equipment of a system embodying 120

the features of this invention the selectors will be arranged in groups each group comprising, say for example, three selectors although any number within a reasonable limit may comprise a group. All of the selectors comprising each group will have their arms 50 arranged so that they will be brought into engagement with the corresponding contact springs in response to the same number of impulses sent over the line but no two groups will have the parts 50 and 52 in contact at the same time. The separate selectors of each group will be so arranged that a different number of impulses will be required to bring the arm 51 into engagement with the contact 52 in the case of each selector although the same number of impulses may be used for bringing the arm 51 and spring 52 into engagement in one selector in each group. This arrangement may be better described by following the operation of the system with reference to Fig. 1.

Assuming in this case that the selectors of group A are adapted to have their arms 50 brought into engagement with the corresponding springs 52 by six current impulses over the line and the selector C of this particular group is arranged to have its arm 51 brought into engagement with the spring 54 in response to four impulses over the line. Now in order to operate the signal controlled by selector C of group A the despatcher starts an impulse transmitter which will first send six current impulses over the line. These six impulses will cause all of the selectors on the line to advance their ratchet wheels 32 six steps bringing the arms 50 of all of the selectors in group A into contact with their corresponding contact springs 52 and establishing a low resistance path around the several holding magnets 30 of this group of selectors. This path may be traced for selector C of group A from point 61 of conductor 62 through conductor 63, arm 50, contact spring 52 and conductor 64 to point 65 of a conductor 66. This will put a dead short circuit around the magnet 30 and a corresponding circuit existing at each of the other selectors in group A the holding magnets of all of the selectors in this group will have their armatures retracted. This will not occur at any of the other groups on the line however, inasmuch as the selectors of group A are the only ones in which the arm 50 is in contact with the spring 52. As battery is kept on the line wires 10 and 11 during the release of the holding magnets the circuit of the stepping magnets 31 will remain intact from line wire 10 through retardation coil 67, conductor 62, conductor 63, arm 50, contact spring 52, conductor 64, conductor 66, winding of magnet 31, conductor 68, resistance 69, retardation coil 70 and conductor 71 to line wire 11. The current in this path will maintain the magnet 31 en-

ergized until the circuit is opened at the despatching station which is the next thing that occurs. This opening however is only momentary and not of sufficient duration to permit the release of the holding magnet 30 armatures of any of the other selectors on the line although of sufficient duration to permit the release of the stepping magnet armature. Following this momentary opening there will be four more current impulses sent over the line to which all of the selectors will respond but only one of which, namely selector C of group A will have its arm 51 brought into engagement with the contact spring 52. Current will now be held on the line wires 80 for a definite length of time and the holding magnet 30 of selector C only of group A will be again short circuited in the same manner as above described and its armature released. The longer arm 51 now being the one in engagement with the contact spring 52 the release of the armature 34 will cause the contact spring 54 to engage contact spring 52 and a circuit will be completed for the signal 60 which may be traced as follows: from one side of battery 72, over conductor 73, conductor 63, arm 51, contact springs 52 and 54, conductor 74, armature of bell 60, contact 75 thereof, conductor 76, winding of bell magnet 60, and conductor 77 to the other side of the battery 72. The opening of the line circuit will release the armature 35 of the stepping magnet 31 which falling back will carry the spring 54 out of engagement with the spring 52 and at the same time permit the ratchet wheel 32 to return to normal position under action, the spring 33 thus opening the bell circuit at two points.

In the same way if it is desired to signal 105 any other station on the line the number of impulses necessary to close the releasing contact for that particular group of selectors will first be sent over the line and then the number of impulses necessary to close 110 the signaling contact of the particular selector in that group.

The selectors are preferably arranged so that the smallest number of impulses necessary to release any particular group of selectors is greater than the greatest number of impulses required to close the signaling contact of any particular selector in the group; thus if there are five selectors in each group the lowest number of impulses necessary to close the releasing contacts should be six, while the number of impulses to close the signaling circuit of an individual selector in the released group may be one, two, three, four or five. This insures that the 125 arms 51 of all of the selectors will always be carried past the position at which they will engage the contact spring 52, thus insuring against confusion of signals and providing a simple code arrangement for signaling. 130

While it may happen that the total number of impulses required to signal any selector of a particular group may be the same as the number required to cause the release of the selectors of a certain other group on the line it will be impossible to close any other signaling contact in response to that number of impulses.

In case the signal 60 is to be operated by current from the battery 18 as shown in group B, the circuit will be as follows: from conductor 10 through retardation coil 67, conductor 62, conductor 63, arm 51, contact springs 52 and 54, conductor 74, contact 75 of the armature of the bell 60, conductor 76, winding of bell magnet 60, conductor 80 to point 81 of conductor 68, and thence through resistance 69, retardation coil 70 and conductor 71 to line conductor 11.

20 I claim:

1. In a selective signaling system in combination line wires, a plurality of selectors connected therewith, impulse sending mechanism for advancing all of said selectors simultaneously, and a normally open shunt circuit associated with each selector closed under the joint control of said impulse sending mechanism and said selectors and cooperating therewith for releasing said selectors at a predetermined position of their movement.

2. In a selective signaling system in combination line wires, a plurality of selectors connected therewith and arranged in groups, a local signal associated with each of said selectors, impulse mechanism for advancing all of said selectors simultaneously and means under the joint control of said impulse mechanism and said selectors for causing the release of selected groups of said selectors and subsequently operating the local signal associated with a particular selector of the released group.

3. In a selective signaling system in combination line wires, having a sending station and a plurality of way stations connected therewith, impulse sending mechanism located at said sending station, a selector located at each of said way stations and a local signal association with each of said selectors, said selectors being arranged in groups, each group being adapted to have its selectors released and returned to normal position in response to a predetermined combination of current impulses and each selector adapted to close a circuit for its local signal in response to a combination of current impulses differing from that required to release any particular group.

60 4. In a selective signaling system the combination with line wires, of selectors connected therewith, each of said selectors embracing an electromagnet, impulse sending mechanism for advancing all of said

selectors simultaneously, means for reducing the current flow through said electromagnet to cause the release thereof, contacts closed by the selectors for controlling said means, said contacts being so arranged that they are closed at different groups of selectors in response to different numbers of impulses, the contacts of all of the selectors in one group being closed in response to the same number of impulses, a signaling circuit for each of said selectors and contacts for said signaling circuits closed at the different selectors in each group in response to a different number of impulses.

5. In combination with a sending station and a way station, impulse transmitting apparatus at said sending station, a step-by-step device at said way station, contact arms carried by said step-by-step device, electromagnetically controlled stepping means and holding means for advancing said step-by-step device in response to current impulses from said sending station, means tending to return said step-by-step device to normal position, means under the joint control of said impulse sending means, one of said contact arms and said electromagnetically controlled means and coöperating therewith for releasing said step-by-step device and under the joint control of said impulse sending means and another of said contact arms for subsequently releasing said holding means, and a signaling circuit controlled by said subsequent release of said holding means.

6. The combination with a sending station and a way station, of impulse transmitting apparatus at said sending station, a circuit closing wheel at said way station, stepping and holding magnets for advancing said circuit closing wheel, means for returning said circuit closing wheel to normal position, means for disabling said holding magnet controlled in two separate positions of said circuit closing wheel, and a signaling circuit closed by the release of said holding magnet in one of the positions of said circuit closing wheel.

7. In combination with line wires, a sending station and a way station connected therewith, a source of current at said sending station, transmitting apparatus at said sending station for connecting said source of current with and disconnecting it from said line wires for predetermined intervals, a selective device at said way station comprising a step by step circuit closing device and stepping and holding magnets operating in response to current impulses from the sending station to advance said circuit closing device, a disabling circuit for said holding magnet, contacts controlled by the advancement of said circuit closing device for closing said disabling circuit, and a signal-

ing circuit, the closure of said contacts in response to a predetermined combination of current impulses from said sending station establishing said disabling circuit for releasing said holding magnet and returning said device to normal position and in response to a different combination of impulses establishing said disabling circuit for

releasing said holding magnet and closing said signaling circuit. ¹⁰

In witness whereof I hereunto subscribe my name this 23rd day of June, A. D. 1911.
